(57) **CLAIM**

The ornamental design for decagonal boxed-wing for aircraft, substantially as shown and described.

DESCRIPTION

FIG. 1 is a perspective view of the design;

FIG. 2 is a front elevation view of FIG. 1;

FIG. 3 is a top plan view of FIG. 1;

FIG. 4 is a side elevation view of FIG. 1;

FIG. 5 is a bottom plan view of FIG. 1; and,

FIG. 6 is a rear elevation view thereof.

The front and rear views are shown in enlarged scale, compared to the dimensions of the top, side and bottom views. As regards the side elevation view, the right-side view is a mirror image of the left side. In the drawings, the broken lines depict environmental subject matter only and form no part of the claimed design. Dash-dot lines illustrate unclaimed boundaries of claimed surfaces.
